UNITED STATES PATENT OFFICE.

GUY C. HEILMAN, OF PHILADELPHIA, PENNSYLVANIA.

BRICK-KILN.

1,237,036.

Specification of Letters Patent. Patented Aug. 14, 1917.

Application filed October 10, 1916. Serial No. 124,755.

To all whom it may concern:

Be it known that I, GUY C. HEILMAN, a citizen of the United States, residing in the city of Philadelphia, county of Philadelphia, and State of Pennsylvania, have invented certain Improvements in Brick-Kilns, of which the following is a specification.

My invention relates to means for burning 10 bricks and it is designed to provide an improved kiln having special means for combining air with fuel gas and distributing the heated products of combustion in contact with the green bricks so as to burn the 15 same expeditiously and uniformly, without the usual smoke and dust.

In practising my invention, in its preferred form, a brick kiln is provided with 20 a gas conduit having discharge passages delivering at intervals within the bottom of 25 the brick chamber, in combination with an air conduit having discharge passages extending through sections of the kiln wall into communication with the gas passages, whereby the air is preheated prior to combination with the gas and highly effective combustion is obtained.

The characteristic features of my invention will be fully understood from the following description and the accompanying drawings in illustration thereof.

In the drawings, Figure 1 is a vertical sectional view taken through a kiln embodying my improvements; Fig. 2 is a part sectional elevation of the same at right angles to the view shown in Fig. 1; and Fig. 3 is a part sectional plan view in illustration of details of the construction.

My improved kiln, as illustrated in the accompanying drawings, comprises the walls 1 supported by the foundations 2, the kiln walls forming a chamber containing the properly spaced stacked bricks 3 through which pass the arches 4. Gas conduits 5 are provided on opposite sides of the kiln and are connected with the interior thereof by the angular passages 6 which extend through the bottoms of the walls 1 and discharge within the arches 4. The flow of gas from the conduits 5 through the passages 6 is regulated by valves 7 and access is provided to the passages by doors 8 which permit inspection and cleaning readily.

Air conduits 10 are disposed on opposite 55 sides of the kiln and are connected by passages 11 with the passages 6 within the walls

1, the air passages being controlled by valves 12 therein. Substantial parts of the passages 11 are disposed within the walls 1 and air flowing therethrough, under control of 60 the valves 12, is heated by the hot surrounding walls of the kiln prior to combination with the gas in the passages 6. A blower 13 supplies the air in the conduit 10 at the desired pressure.

The products of combustion from the combined air and fuel gas, which burn within the passages 6, flow through the arches 4 from which they are disseminated laterally and upwardly through the properly spaced 70 bricks which are heated uniformly and expeditiously thereby, without the smoke and waste attending usual brick burning operations.

Peep holes 14 are formed in the walls 1 above the passages 6, expanding from the outside inwardly and providing means for viewing the space within the arches 4, the outer ends of the holes being covered by transparent covers 15, such as plates of mica. 80

Having described my invention, I claim:

1. A brick kiln having walls forming a heating chamber, a fuel gas conduit having in a wall aforesaid a section discharging into said chamber, and an air conduit having 85 in a wall aforesaid a section communicating with said section first named thereby producing a mixture of air and gas within said wall, in combination with an arch into and through which the heated products of combustion flow.

2. A brick kiln having walls forming a heating chamber, a fuel conduit having passages extending through a wall aforesaid at spaced intervals into the bottom of said chamber, and an air conduit having passages extending through said wall into the respective passages first named, thereby producing a mixture of air heated by said wall and gas in said passages first named, in combination with arches into and through which the heated products of combustion flow.

3. A brick kiln having walls forming a heating chamber, a fuel gas conduit having angular passages extending through a wall 105 aforesaid into the bottom of said chamber, valves for controlling the flow of gas through said passages and doors for permitting access to said passages, in combination with an air conduit having angular passages 110 extending through said wall into the respective passages aforesaid to effect within said

wall a mixture of gas and heated air, and valves for controlling said passages second named.

4. A brick kiln having walls forming a heating chamber, a fuel gas conduit having passages extending into the bottom of said chamber, an air conduit having passages heated by a wall aforesaid and communicating with said passages first named there-

by producing a mixture of heated air and 10 gas in said passages first named, a blower for forcing air through said air conduit, and peep holes in said wall adjacent to the respective passages.

In testimony whereof, I have hereunto set 15 my name this 2nd day of October, 1916.

GUY C. HEILMAN.
